UNITED STATES PATENT OFFICE.

FERDINAND W. STARR, OF SPRINGFIELD, OHIO, ASSIGNOR OF ONE-HALF TO THOMAS WALL, OF SAME PLACE.

MACHINE FOR OILING AND POLISHING WHEELS.

SPECIFICATION forming part of Letters Patent No. 319,636, dated June 9, 1885.

Application filed March 6, 1885. (No model.)

To all whom it may concern:

Be it known that I, FERDINAND W. STARR, of Springfield, in the county of Clark and State of Ohio, have invented certain new and 5 useful Improvements in Machines for Oiling, Polishing, and Finishing Vehicle-Wheels, of which the following is a specification.

My invention relates to a machine for finishing vehicle-wheels; and it consists, essentially, 10 in a box or receptacle somewhat larger than the wheel to be polished, filled with the necessary material for polishing, a stud or journal to support the wheel within said box, and means for moving the wheel through or over 15 the polishing material; all as hereinafter more fully set forth.

In the accompanying drawings, Figure 1 is a top plan view of the machine; Fig. 2, a vertical central section of the same, and Fig. 3 an 20 enlarged detail view.

The object of this invention is to provide means for oiling, polishing, and finishing vehicle-wheels, whereby the labor is decreased and the wheel uniformly, thoroughly, and 25 quickly oiled and polished.

In the drawings, A indicates a box or receptacle the sides *a* of which are preferably made of sheet metal, said box being supported upon legs *b* and provided with a bottom, *c*, the 30 latter made, preferably, of wood. The bottom is provided with an opening, *d*, in its center, as shown in Figs. 1 and 2, said opening being of a width somewhat greater than the diameter of the hub of the wheel to be finished.

Upon the under side of the bottom *c*, and pivoted thereto at *e*, is a lever, *B*, one end of 35 which extends out beyond the side of the box, as shown, and the body of which is enlarged at a point immediately below the opening *d*, so that the latter will be entirely covered whatever may be the position of the lever *B*. The operating end of lever *B* is held up to the under side of the box or receptacle A by means of a cross-bar, *f*, extending from one 40 leg *b* to another, as shown in Fig. 2. As shown in Figs. 2 and 3, the lever *B* is provided with an upright spindle, *g*, which extends above the lever a considerable distance, and is provided with nuts *h*, while its lower end 45 passes through the lever and is furnished with a band wheel or pulley, *i*, firmly secured there-

upon. At the point where spindle *g* passes through lever *B* the latter is provided with a bushing or collar, *j*, as shown more clearly in Fig. 3, which not only prevents undue wear 55 of the lever, but also serves to protect the upper and lower faces of the lever against wear. The box or receptacle A and the opening *d* are filled or partially filled with sawdust, shavings, turning-chips, excelsior, or any 60 similar material, *G*, and then sprinkled or advisably saturated with linseed-oil or other suitable substance. The hub of the wheel to be cleaned is then placed on the spindle *g*, the spokes resting upon the upper face of the bottom *c*, or upon the shavings, &c., therein, while the hub extends down into the opening *d*, as clearly shown in Figs. 2 and 3, the wheel being secured upon the spindle *g* by the nuts *h*, as indicated. After the wheel has thus been 70 placed in position and the box or receptacle is filled with the saturated material *G*, it is only necessary to move the lever *B* from side to side upon its pivot *e*, the wheel of course moving with it. This reciprocating action 75 causes the saturated material *G* to rub against all parts of the wheel, and not only serves to smooth the same, but allows the oil contained in the material to enter the pores of the wood, and thus color the wheel uniformly throughout. The reciprocation of the lever can be performed by hand or by any suitable mechanism, as preferred, and the wheel may be turned from time to time by hand or otherwise to present different surfaces, and to cause 80 the rubbing to be performed in different directions. In some cases it is desirable to give the wheel a rotary motion instead of or in addition to the reciprocating motion; and to accomplish this I provide the spindle *g* with 85 a band-wheel, *i*, below the lever *B*, as above mentioned, to which rotary motion may be imparted from any convenient source, thus causing the wheel carried by the spindle to rotate at the same time that it is being reciprocated, or when the wheel is otherwise at rest.

In order to cause the wheel to revolve with the spindle, the nuts *h* on the upper end of the latter must be screwed down upon hub, to 90 press its lower end against collar *j* upon the spindle *g*, and thereby produce sufficient fric-

tion to lock the wheel and spindle together; or a clutch-arm, *k*, may be employed, as shown in Figs. 1 and 2. Ordinarily, either the reciprocating or rotary motion will be found to 5 answer well; but when they are combined the action of the machine is improved and made more rapid.

It is apparent that the wheel may be stationary and the box or receptacle made to 10 revolve, this construction being simply a reversal of the plan shown in the drawings.

The machine in practice has been found to 15 give excellent results, the wheel after leaving it being very smooth, thoroughly oiled, and possessing a finely-polished and finished appearance. By applying the oil in this manner it is applied in small quantities and evenly 20 over the entire wheel and rubbed in thoroughly, whereas when the oil is applied by brush 25 or cloths in the usual manner it accumulates in spots, holds the dust, takes considerable time for drying, and many points are liable to be left unfinished.

When the wheel is removed from the 25 machine, it is only necessary to wipe off the fine particles of fiber which cling to it, and it is ready for shipment or use.

The principle object of my invention is to 30 accomplish more perfectly and expeditiously what has heretofore been done by hand. It is particularly useful in cleaning wheels that have become discolored from exposure, giving to such wheels an entirely fresh and new appearance. Instead of simply saturating the 35 material *G* with oil, it is apparent that it can be impregnated with any suitable wood-filling material which will fill up the pores of the wood preparatory to painting the wheel. The lever *B*, carrying the wheel, can be operated 40 in any suitable manner, the drawings showing an arm connected to the lever and carried by a rock-shaft. It will be seen that the lever *B* can extend over the upper side instead of the 45 lower side of the box, in which case the weight of the wheel and lever is sufficient to produce the required friction, the bottom *c* of the box being in such case closed.

I am aware that a machine for painting 50 wheels has been provided with a tank to contain liquid paint and a central spindle to sustain the wheel, the spindle being furnished with a spring to lift the wheel out of the paint; and I am further aware that it has been suggested that the spindle of such apparatus 55 might be rotated after the wheel is lifted out of the paint to throw off the surplus paint.

I make no claim to such painting apparatus.

Having thus described my invention, what I claim is—

60 1. In a wheel-polishing machine, the combination of a box or receptacle containing a polishing material and a spindle or holder

within the box for holding the wheel, said spindle or holder and box being arranged substantially as described, whereby one of said parts may be moved relatively to the other. 65

2. In a wheel-polishing machine, the combination of a box or receptacle containing a polishing material and a spindle or holder within the box for holding a wheel, said spindle or holder being arranged substantially as shown and described, whereby it may be reciprocated within the box. 70

3. In a wheel-polishing machine, the combination of a box or receptacle for containing a polishing material and a spindle or holder within the box for holding a wheel, said spindle or holder being arranged substantially as described, whereby it may be rotated within the box. 75

4. In a wheel-polishing machine, the combination of a box or receptacle containing a polishing material, and a spindle or holder within the box for holding a wheel, said spindle or holder being arranged substantially as shown and described, whereby it may be rotated and reciprocated simultaneously within the box, for the purpose set forth. 80

5. In combination with box *A*, having sides *a* and bottom *c*, the latter provided with opening *d*, lever *B*, pivoted to the box and carrying a spindle or holder to support the wheel, and suitable material, *g*, for smoothing and oiling the wheel, as set forth. 85

6. In combination with box *A*, constructed substantially as shown and described, lever *B*, provided with spindle *g*, said spindle or holder being provided with nut *h* and band-wheel *i*, as set forth. 90

7. In combination with box *A*, having sides *a*, legs *b*, bottom *c*, and opening *d*, lever *B*, pivoted to the box and provided with spindle or holder *g*, nut *h*, wheel *i*, and collar *j*, as and for the purpose set forth. 95

8. In a wheel-polishing machine constructed substantially as shown and described, lever *B*, pivoted to the box and carrying a spindle or holder for the wheel to be polished, said lever being enlarged immediately around the spindle, as and for the purpose set forth. 100

9. A machine for operating upon the surface of vehicle-wheels, consisting, essentially, of a receptacle for holding the abrading or polishing material and an arm or holder or the equivalent thereof by which the wheel is held and reciprocated or rotated, or both, over and among the polishing or abrading material contained in the receptacle, for the purpose of cleaning, oiling, or imparting a smooth surface to the wheel. 105
